(57) **CLAIM**

I claim the ornamental design for a respirator mask, as shown and described.

DESCRIPTION

FIG. 1 is a front perspective view from above of an embodiment of the claimed design;

FIG. 2 is a rear perspective view of the claimed design of FIG. 1;

FIG. 3 is a top view of the claimed design of FIG. 1;

FIG. 4 is a bottom view of the claimed design of FIG. 1;

FIG. 5 is a left side view of the claimed design of FIG. 1;

FIG. 6 is a right side view of the claimed design of FIG. 1;

FIG. 7 is a front view of the claimed design of FIG. 1; and,

FIG. 8 is a rear view of the claimed design of FIG. 1.

The broken lines in the drawings illustrate portions of the respirator mask that form no part of the claimed design.

1 Claim, 8 Drawing Sheets
